UNITED STATES PATENT OFFICE

JOHN C. LEARY, OF SAN FRANCISCO, CALIFORNIA

PISTON-GUIDING MEANS.

Application filed December 17, 1923. Serial No. 681,179.

My invention relates to a means for preventing piston slap in an internal combustion engine, particularly during the power stroke.

5 An object of the invention is to provide an internal combustion engine in which a piston and crank are directly connected by a connecting rod, with means incorporated with the piston and cooperating with means provided in the crank case for preventing rocking of the piston and the attendant deleterious effects.

Another object of the invention is to provide means of the character described which 15 is extremely light and inexpensive in construction and does not require any material change in the design of the engine.

A further object of the invention is to provide means of the character described which 20 will not interfere with the operating efficiency of the engine.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the 30 said drawings and description, as I may adopt variations of the preferred form within the scope of my invention as set forth in the claims.

Referring to said drawings: 35 Figure 1 is a longitudinal sectional view of an engine equipped with the means of my invention.

Figure 2 is a view similar to that of Figure 1 showing a modified form of the means.

40 As is well known, the piston and cylinder of an internal combustion engine of the usual type are subjected to considerable frictional wear on one side due to the rocking of the piston during the explosion stroke. This 45 rocking is due to the fact that the connecting rod is angularly disposed with respect to the axis of the cylinder during the working stroke, and, therefore, exerts a transversely acting thrust against the cylinder wall 50 through the piston at the side away from

which the connecting rod moves during the first half of said stroke. Many attempts have heretofore been made to remedy this objectionable feature, but the majority of such attempts, in accomplishing the desired end, 55 have more or less impaired the efficiency of the engine. In accordance, however, with my invention the objectionable side play of the piston is not only eliminated but the operating efficiency of the engine is fully preserved. 60

Briefly expressed, the means of my invention in the preferred embodiment comprises a piston having incorporated therewith a rigid yoke which extends longitudinally 65 thereof and encircles the connecting rod and crank pin. Cooperating guide members are provided on the yoke and crank case which serve to guide the yoke for movement parallel to the axis of the cylinder during the reciprocation of the piston and thereby prevent 70 rocking of the piston. Means are also provided for supplementing the guiding action of the guide members and causing the piston to move in the proper path even though the 75 side of the piston and cylinder have become worn.

A detailed description follows:—

As hereinbefore stated the means of my invention is adapted for use in connection 80 with an internal combustion engine in which the crank and piston are directly connected by a connecting rod. Accordingly, in the drawings the engine 4 is provided with a piston 5 which is mounted for reciprocation 85 in a cylinder 6 and is operatively connected to the crank shaft 7 by means of a connecting rod 8 and crank 9.

Rigidly fixed to the piston, of which it is 90 virtually a part, by means of bolts 12 or the like and extending into the crank-case 13 is a yoke or strap 14 preferably of segmental cross section. The yoke 14, together with the piston proper, extends completely around the connecting rod including the wrist pin 16 95 and crank pin 17, and defines a plane parallel to the plane of motion of the connecting rod. Due to the position of the yoke relative to the connecting rod, the former is of such shape as to not interfere with the oscillation 100

of the connecting rod. Fixed to the yoke, preferably at a point longitudinally aligned with the cylinder, which point is preferably most remote from the piston proper, is an extension 18 which is in slidable engagement with a guideway 19 formed in the wall 21 of the crank-case 13. As here shown, the extension 18 is in the form of a cylindrical rod 22 which moves in a direction parallel to the axis of the cylinder and reciprocates in the cylindrical bore 23 of the guideway 19. It will thus be noted that the portion of the piston engaging the walls of the cylinder will be prevented from moving in any direction other than axially of the cylinder. Thus rocking of the piston is absolutely prevented.

The piston proper is provided with cored walls, so that the combined weight of the piston including the yoke portion is no more than the weight of the usual piston, and since the side thrust of the piston is distributed so that the unit pressure on the bearing surfaces involved is reduced to a minimum, wear of the parts will be correspondingly reduced and the efficiency of the engine will be preserved.

Adjustably positioned in the crank case is a roller 31 which is adapted to bear against the side 32 of the piston from which the connecting rod moves during the first part of the working stroke. In this manner, if the side 32 of the piston or the cylinder wall portion 33 engaged thereby becomes worn the roller may be adjusted to cooperate with the guide members 18 and 19 to hold the piston to its proper path.

In Figure 2, a slightly modified form of guiding means is shown. In this embodiment, extensions 34 at opposite sides of the yoke are formed with bearing faces 36 which are arranged to engage bearing surfaces 37 provided on the adjacent sides of the crank case.

I claim:

45 1. In an internal combustion engine, the combination with a piston mounted for reciprocation in a cylinder and attached to a crank by a connecting-rod of an adjustably positioned roller adapted to bear against the piston at the side away from which the connecting rod swings during the first part of the power stroke.

50 2. In a piston guiding means, the combination with a cylinder, a piston mounted for reciprocation therein and a connecting rod at one end of the piston, said piston being reduced in cross sectional area adjacent said rod whereby such reduced portion will be kept spaced from the walls of the cylinder when disposed therein, and an adjustable non-friction bearing member arranged to engage said reduced portion of the piston during the reciprocation thereof.

55 3. In piston guiding means; the combination with a cylinder; a piston mounted for

reciprocation therein; a connecting rod at one end of the piston; said piston being reduced in cross sectional area adjacent said rod whereby such reduced piston will be kept spaced from the walls of the cylinder when disposed therein; a yoke member rigidly fixed at an end to, and forming an extension of, the piston and disposed about said rod; means adjacent the other end of said yoke for guiding same in axial alignment with the piston during the reciprocation thereof; and means engaging the said yoke member at the first end thereof for guiding same during said reciprocation.

In testimony whereof, I have hereunto set my hand at Oakland, California, this 15th day of November, 1923.

JOHN C. LEARY.
